PLASTIC BARGE FOR CRYOGENIC SERVICE
Harold R. Pratt, Ridgewood, N.J., assignor to Esso Research and Engineering Company, a corporation of DelawareFiled Jan. 18, 1965, Ser. No. 426,271
3 Claims. (Cl. 114—74)

The present invention relates to barge constructions, and more particularly to barges adapted to transport cryogenic cargoes, such as liquefied natural gases at atmospheric pressures.

It has been established that the transportation of gases, such as nitrogen, methane, and the like, to remote locations may best and most efficiently be accomplished by reducing the volume of the gas through its conversion into the liquid state. Such a conversion enables the storage volume requirements to be greatly reduced (approximately six-hundredfold for a given quantity of methane gas, for example) and, as should be appreciated, enables the most efficient transfer of the gas to a remote area.

In order to transfer liquefied gas in a practical and economical manner in relatively large volumes, it is necessary to store the liquefied gas at approximately atmospheric pressure, since large vessels built to withstand superatmospheric pressures would be impractical, if not impossible to construct for use in or on barges, seagoing tankers or the like. Moreover, liquefied gases maintained at atmospheric pressures have extremely low vaporization points, ranging from about -435° F. for liquefied hydrogen, to -28° F. for liquefied ammonia, and these unusually low temperatures of the liquids present certain problems. Specifically, the vessels must be sufficiently thermally insulated to be capable of preventing heat losses which would lead to subsequent vaporization of the stored liquefied gas. They also must be of sufficient strength in the cold condition to withstand the often substantial internal stresses that may be induced herein by the large temperature gradients through its walls.

Heretofore, the proposed solutions to the problem of safely and reliably transporting liquefied gases at cryogenic temperatures and atmospheric pressure have utilized separately insulated liquid and gas impermeable containers which are, themselves, independently, integrally, or otherwise installed in otherwise generally conventional ships or barges. Furthermore, in the interest of safety and in conformance with maritime regulations, the conventional steel vessel structure, which is subject to damaging embrittlement by leakage of the cryogenic liquefied gas cargo, has been separated from the supercooled cargo by more than one liquid and gas impermeable barrier.

The present invention represents an entirely new approach and an improved solution to the problems associated with the marine transportation of liquefied gases at cryogenic temperatures. Specifically, the ship, the thermal insulation, and the cryogenic container are fabricated as one and the same from special stepped plastic structural members or panels, made in accordance with general precepts set forth in detail in my copending application Serial No. 394,287, filed September 3, 1964, for "Insulation System." In accordance with the invention, the plastic panels possess sufficient insulating and strength properties to prevent vaporization of the liquefied gas and to retain the integrity, seaworthiness, and cargo-impermeability of the ship.

The insulated cryogenic container of the invention is built in the general form of a closed barge, using a series of stepped, interlocking plastic panels. The panels themselves are formed of fiberglass reinforced polyester resin shells filled with foamed polyurethane. In the barge of the invention, each of the joints between adjacent,

2

matingly stepped panels is made fast and liquid-tight by means such as an epoxy adhesive.

As will be appreciated, the new barge, as a single structure, functions in the multiple capacities of what heretofore required several distinct structural entities, i.e., a container system, an insulating system, and a ship, which were themselves interrelated by sometimes complicated mounting systems to accommodate differential rates of expansion. Furthermore, since the barge is constructed entirely from plastic, the elimination of steel from the structure obviates the requirement for additional or secondary barriers and/or insulation to protect the steel from the cryogenic cargo. Accordingly, a multiple-functioning barge may be constructed in accordance with the invention with a significant savings in material and labor costs in comparison with conventional marine transportation systems for cryogenic cargoes.

For a more complete understanding of these and other attendant advantages of the present invention, reference should be made to the following detailed description taken in conjunction with the accompanying drawing in which:

FIG. 1 is a longitudinal cross-sectional view of a new and improved barge embodying the inventive concepts;

FIG. 2 is a plan view of the barge shown in FIG. 1;

FIG. 3 is an enlarged cross-sectional view of the new and improved barge taken along line 3—3 of FIG. 1;

FIG. 4 is an enlarged, fragmentary, cross-sectional view of the barge taken along line 4—4 of FIG. 3; and

FIG. 5 is a further enlarged, fragmentary, cross-sectional view showing details of construction of the walls of the new and improved barge.

Referring to FIG. 1, the barge of the present invention is generally symmetrical in overall shape and includes a hull having forward and after hull portions 10 and 11, respectively, and an intermediate hull portion 12. As shown, the hull itself is closed by a deck 13 to define a cargo space which may be divided by transverse bulkheads 14 and a longitudinal bulkhead 15 (FIG. 3), to define a plurality of cargo holds 15a. Access to the cargo space is had through hatches 16 (FIG. 2) formed in the deck 13.

In accordance with the principles of the invention, the entire barge structure is fabricated from plastic panels 17 which act in a dual capacity as thermal insulators and rigid load bearing structural members. More specifically, and as shown in FIGS. 4 and 5, each of the plastic panels 17 includes a shell 18 of polyester resin reinforced with sufficient fiberglass to impart significant and adequate structural strength, which shell is filled with a cellular insulating material, such as polyvinylchloride or polyurethane foam 19. The principal inner and outer shell surfaces are joined and held in spaced relation by a plurality of integral transverse web sections 24. The connecting web sections divide the individual panels into a plurality of sections or cells and, in conjunction with the foam material filling the cells, impart significant structural rigidity to the panels. Certain additional details of the panel construction are reflected in my copending application Serial No. 394,287, filed September 3, 1964, "for Insulation System."

The peripheries 20 of the respective panels 17 are of predetermined stepped configuration to interlock matingly with one another, in accordance with the principles of the invention. As illustrated particularly in FIG. 5, the panel margins advantageously include peripheral flanges 25 received in corresponding recesses 26 in adjacent panels. The stepped peripheral configuration of the panels, in conjunction with the flanges 25, provides substantial longitudinally and transversely oriented surface areas for bonding, to provide a liquid-tight structural sound joint. Special, stepped connecting pieces, such as

indicated at 27, 28 in FIG. 3, may be utilized to join panels at corners and other places of intersection. The construction of the connecting pieces is of insulating foam material encapsulated in a shell of polyester resin and fiberglass, similar to construction of the panels themselves.

The hull walls 22 of the barge, as well as the bulkheads 14, 15 and the deck 13, are fabricated from groups of contiguously arrayed panels 17 united at their peripheries by an interposed epoxy adhesive 21 or the like (FIG. 5) to form stable, liquid-tight joints 23. In accordance with the principles of the invention, the completed plastic structure, a navigable barge, is capable of bearing the hydrostatic loads imposed by the liquefied gas cargoes as well as capable of withstanding the induced thermal stresses of the cryogenic cargoes.

Alternatively, as found necessary or where desirable, large sections of the barge, having a similar fiberglass reinforced polyester shell and urethane foam construction, may be pre-molded, or otherwise prefabricated, and later joined by a stepped and glued arrangement such as described hereinabove and in the aforementioned copending application. Such a construction would, of course, significantly reduce the number of joints necessary in a barge of a given size.

It should be appreciated that, in accordance with the principles of the present invention, a barge may be constructed with minimum effort and material, since the barge itself functions as a thermally insulated container. In other words, significant economies in production are realized, by incorporating the vessel, cargo container, and thermal insulation into a single autonomous unit rather than having three or more separate structures.

The new and improved plastic barge is intended primarily for still water service, such as in rivers and canals, and is designed to possess sufficient structural integrity for that purpose and, additionally, to possess sufficient thermal insulating properties to prevent the undue warming and consequent volatilization of liquefied gas cargoes. This advantageous structure is achieved without the use of metallic or like embrittleable structural members.

It should be understood that the specific mode of construction herein illustrated and described is intended to be representative only, as certain changes may be made therein without departing from the clear teachings of the disclosure. Accordingly, reference should be made to

the following appended claims in determining the full scope of the invention.

What is claimed is:

1. A rigid barge for transporting cryogenic cargoes at atmospheric pressure comprising
  - (a) a deck portion,
  - (b) a rigid hull having forward and after portions and intermediate cargo-carrying portions, said cargo carrying portions cooperating with said deck portion to define a closed liquid carrying cargo hold,
  - (c) said hull and deck portion being substantially entirely fabricated from rigid load bearing insulation panels,
  - (d) said panels being matingly stepped at their peripheries,
  - (e) said panels also having fiberglass reinforced polyester resin shells filled with a suitable insulating foam and a plurality of integral transverse web sections between the principal inner and outer shell walls,
  - (f) said integral web sections being constructed of fiberglass-reinforced-polyester and of sufficient strength to contribute to the overall structural rigidity of said insulation panels.
2. The barge of claim 1 including
  - (a) adhesive means bonding together adjacent panels at their matingly stepped edges in an effectively continuous, stable and liquid-tight manner.
3. A rigid barge in accordance with claim 1, in which
  - (a) said insulating foam is chosen from the group including polyvinylchloride and polyurethane.
